UNITED STATES PATENT OFFICE.

JOSEPH P. GIBSON, OF DAYTON, OHIO.

DESIGN FOR A CHAIR.

47,036.

Specification for Design.

Patented Mar. 2, 1915.

Application filed December 18, 1914. Serial No. 877,995. Term of patent 7 years.

To all whom it may concern:

Be it known that I, JOSEPH P. GIBSON, a citizen of the United States, residing at Dayton, in the county of Montgomery and State of Ohio, have invented a new, original, and ornamental Design for Chairs, of which the following is a specification, reference being had to the accompanying drawing, forming a part thereof.

The figure is a perspective view of a chair, showing my new design.

I claim:

The ornamental design for a chair as shown.

JOSEPH P. GIBSON.

Witnesses:

R. J. McCARTY,
MATTHEW SIEBLER.
